UNITED STATES PATENT OFFICE

ALFRED W. SCHULTZ, OF WATERLOO, IOWA, ASSIGNOR TO THE ZEIDLER CONCRETE PRODUCTS MACHINERY COMPANY, OF WATERLOO, IOWA

MACHINE AND METHOD FOR CONSTRUCTING CONCRETE PIPE

Application filed July 2, 1928. Serial No. 289,682.

My invention relates to improvements in machines and methods for constructing concrete pipe tile or conduits, with or without reinforcing, and the object of my improvement is to supply a method and an apparatus for cooperating with such a machine to produce in the terminations, bell-ends or other formed ends, of concrete pipe tile or conduit sections a stronger and more consolidated construction and so cohesive as to render such terminal parts proof against any stresses thereagainst or accidental ruptures and especially at reentrant angles thereof where most exposed to breakage in handling, storing, shipping or while being placed in position with others in a trench or other place.

This object I have accomplished by the method and by the mechanism which are hereinafter described and claimed, and which are illustrated in the accompanying drawings, in which Fig. 1 is a vertical central or axial section of the conjoint means for forming a section of concrete pipe including my device for jarring and consolidating the plastic contents of a bell-end or other shaped termination of the section according to the principle of my invention, parts of the mechanism being broken away. Fig. 2 is a top plan of the cam-carrier device of the invention.

My invention in both its method and mechanism is not restricted to the precise process nor to the exact construction and arrangement of parts of the mechanism by which the method is effected and herein shown and described, nor to the various details thereof, as both may be modified, varied or rearranged in various ways and particulars without departing from the spirit and scope of my invention, one practical method of which has been herein described and exemplified specifically without attempting to show all of the various modes and forms and modifications in which the invention might be shown.

I have herein added improvements upon the patent to Schenk and Stewart, No. 1,248,018, for tile machine, the property of the assignee of this application.

My invention includes a relatively fixed table 1 having an aperture 2. A spider 3 has divergent arms bent upwardly and secured

by screws 4 to the lower face of the table, with stems projecting thereabove.

A rigid axial stud or pin projects upwardly at 12 from the center of a cam-carrier disk 10 having a short depending cylindrical shaft or boss 9 seated rotatably in a shallow upwardly opening step-bearing 8 at the center of said spider 3. The upper end part of the pin 12 is transversely apertured to seat therethrough a cross-pin 13.

The numeral 7 denotes a substantially cylindrical hollow mold-casing whose lower part is expanded at 6 in a well-known way for the formation therein of a bell-end of a section of concrete pipe whose cylindrical hollow body is shaped within the cylindrical body of the casing thereabove. This mold-casing may be constructed of a pair of like halves adapted to be secured together by any desired means for use or for disassembly as well known to those skilled in this art. Angular bar supports 5 are fastened to the bell of the mold-casing their horizontal terminations being apertured to seat removably on said screw stems 4, with the mold-casing 65 concentric with and above the disk 10 and its central pin 12.

The numeral 14 denotes a pallet mounted removably on lugs on the supports 5 and having its central part raised upwardly annularly with a central circular aperture concentric with the axis of the mold-casing.

The numeral 19 denotes a hollow former-head with cylindrical outer wall and of a diameter slightly less than the diameter of the central aperture of the pallet 14, the former-head having a closed top and open bottom and having a central interiorly threaded opening to seat the diminished exteriorly threaded lower end 22 of an axial shaft part which is expanded at its upper end 24 and cupped to mate with a diminished termination of the rotatable shaft 23, the latter being rotated by any suitable mechanism which includes means for simultaneously reciprocating it and said former-head 19 through the mold-casing 7. A pair of like troweling bodies 25 are mounted upon the shaft lower section immediately above the former-head 19. Both the former-head and

said troweling bodies serve while they are being simultaneously rotated and reciprocated in and through said mold-casing 7 to shape and trowel accurately the longitudinally hollowed tile being formed within 5 the casing from deposited plastic materials.

The threaded termination 22 of the shaft projects downwardly below the closed upper end of the former-head 19 to seat thereon a 10 socketed cap or extension 20 whose lower end is socketed at 26 to be seated centrally upon the raised pin 12, and also transversely grooved at 21 to seat over and engage the end parts of the cross-pin 13. By this means, the 15 disk 10 may be rotated while said parts are coengaged as the former-head is at its lowermost position and has a momentary cessation of reciprocation due to cam-mechanism not shown but such as is well-known in this 20 art.

A flat ring 15 is removably secured by screws to the supports 5 spaced vertically below the pallet 14 concentrically and is apertured at 16 in a number of places concentrically to loosely seat headed pins or tappets 17 whose heads are immediately below the annular bottom outer part of the pallet. The disk 10 has radial ribs 11 upon its upper surface which are triangular in cross-section and which serve as cams into whose path of rotation the lower rounded terminations of the stems of the tappets 17 extend, so that when the disk 10 is in rapid rotation the tappets in succession ride upwardly upon these 25 ribs 11 and rap their heads upon the lower annular rim part of the pallet 14 thereabove, thus imparting to the pallet all around a succession of jarring blows for a purpose to be described. To prevent any sticking of the 30 tappets, a coiled light compression spring 18 may be mounted around the lower projecting part of each engaged between the ring 15 and a pin inserted in an aperture in the end of the tappet.

Concrete material in a plastic aqueous mixture of relatively coarse sand, with or without small particles of rock, and finely comminuted cement, having been deposited by means not shown intially within the mold-casing 7 and during the operation of forming a tile section therein, is delivered into the interspace of the pallet 14 and the bell-end 6 of the mold-casing immediately before and during the troweling action of the troweling 55 bodies 25 when moving upwardly and rotating. By this means the tile is ordinarily formed of a homogeneous consistency. It has been found that the bell-end of the tile is peculiarly susceptible to breakage particularly at its angles by handling and positioning in assemblage with others.

I have discovered that the bell-ends of such tile, or in fact any tile termination, may be differentially strengthened and fortified 60 against such stresses and shocks as are met

in practice, by constructing these terminations of a richer mixture of the cementitious elements of the plastic concrete used for the tile. This differential construction may be effected by different methods and by means 70 of different mechanisms, of which the one illustrated is typical.

A differential settling of the concrete mixture in the bell-end part only of the mold-casing 7 is effected by intermittent jarring 75 of either the bell-end 6 of the mold-casing or of the outer annular part of the pallet 14. The rapid light and repeated jarring of either causes a partial separation of the ingredients of the mixture because of their flowable condition in the loosely plastic mass, so that the finely comminuted particles tend to seek the bottom of the bell-end of the forming tile structure in passing through the interstices of the larger particles of sand or rocky substances, and as these finer particles are cementitious and more closely consolidated as thus differentially separated and settled, the bell-end at the bottom and more gradually mixed upwardly is, when dried out, more solid than 85 the general and homogeneous substance of the body of the tile thereabove and harder and more resistant at the inner reentrant angles. This differential settling is shown in Fig. 1 at the bottom part of the mold-casing between it and the pallet 14 by the more closely compacted dots indicating this 90 resistant and separately settled cementitious ingredient which gradually merges with the coarser ingredients above.

The bell-end of a tile section thus constructed is not only much stronger to resist shocks, but less impervious than other parts of the tile, and also smoother exteriorly which insures better fitting of the assembled 100 tiles in alinement. The method is operative 105 without any change in the tile-forming mechanisms, and without delay in the manufacture, as the action of the jarring device is entirely automatic.

Having described my invention, what I claim as new, and desire to secure by Letters Patent, is:

1. The method of differentially consolidating a termination of a concrete pipe section, which consists in subjecting the mixed concrete in the end part of a molding device to light intermittent jarring before troweling the tile body thereabove.

2. The method of differentially consolidating and settling mixed concrete materials in plastic condition in a bell end part of a molding device, by subjecting the latter to rapid intermittent jarring while the materials are being delivered into said end part and before the troweling of the body of the tile thereabove.

3. The combination with a molding device, of cooperating mechanisms operative to rapidly intermittently jar the contents of a 130

part of said device before the troweling of another part to cause differential settling in the lower part of the device of finer from coarser ingredients of a plastic mixture deposited in the device.

5. 4. The combination with a molding device having a lower portion adapted to shape a termination of a hollow tile to be molded therein, of means for rapidly tapping said lower portion to differentially settle the mixed plastic ingredients of a mixture deposited in the device to produce a termination on the formed tile of harder and stronger consistency than the body of the tile.
10. 10. 5. The combination with a mold to shape a concrete body from a mixture of flowable finer and coarser ingredients, of mechanisms associated with said mold comprising a plurality of tappets mounted movably in a desired arrangement relatively to an end part of the mold, means for causing said tappets to strike said end part in repeated succession, and a rotary troweling device to simultaneously trowel said mixture in said end part
15. 20. 25. immediately after said tapping operation.
6. 6. The combination with a mold to shape a concrete body from a mixture of flowable finer and coarser ingredients, of a mechanism associated with said mold comprising a plurality of tappets movable to and from an end part of the mold to tap the same in moving in one direction, and a rotary cam device adapted to impinge upon said tappets in succession to cause them to intermittently jar the said end part of the mold to cause differential settling of the concrete materials in said end part.
30. 35. 40. 45. 50. 7. The combination with a mold to shape a concrete body from a mixture of flowable finer and coarser ingredients, of a mechanism associated with said mold comprising a plurality of tappets movable to and from an end part of the mold to tap the same in moving in one direction, means for resiliently controlling said tappets, and a rotary cam device adapted to impinge upon said tappets in succession to cause them to jar said end part of the mold and cause a differential settling of the components of the concrete mixture to settle the finer ingredients below the coarser ingredients thereof in said end part.

In testimony whereof I affix my signature.
ALFRED W. SCHULTZ.
